RICHARD CHARLTON, OF LIVERSEDGE, ENGLAND, ASSIGNOR TO W. & SLOANE, OF NEW YORK CITY.

Design No. 4,943, dated May 30, 1871.

DESIGN FOR A CARPET-PATTERN.

The Schedule referred to in these Letters Patent and making part of the same.

To all whom it may concern:

Be it known that I, RICHARD CHARLTON, of Liversedge, in the county of York, England, have invented a new and original Design for Carpeting, of which the following is a specification.

The nature of my design is fully represented in the accompanying photographic illustration, to which reference is made.

I claim as my invention—

The design for a Brussels carpet, as shown.
December 30, 1870.

RICHARD CHARLTON.
